UNITED STATES PATENT OFFICE

JOHN FREDRIK HALSTEAD, OF BROOKLYN, NEW YORK, ASSIGNOR TO INTERNATIONAL CIGAR MACHINERY COMPANY, A CORPORATION OF NEW JERSEY

CIGAR-BUNCH MANIPULATOR

Application filed August 30, 1928. Serial No. 303,056.

This invention relates to improvements in cigar bunch manipulators designed particularly for use in cigar machines to prepare the freshly rolled bunches for shaping or crimping operations. The filler of a freshly 5 rolled bunch is usually unevenly compacted and it is common, in making cigars by machinery, to provide a bunch manipulator in which bunches are rolled between a rotating drum and a concave surface, between which the bunches are slightly squeezed to thereby 10 evenly distribute the tobacco within the bunch.

Hitherto, in manipulators of this type, the 15 bunch has been delivered on one side of the drum, rolled approximately half way round the drum and ejected on the opposite side. It is an object of the invention to provide a manipulator in which the bunches pass 20 almost completely around the drum, to be ejected at a position adjacent the delivery position. This arrangement makes possible an improved manipulator which is simpler and more compact, and in which the drum 25 and concave member may be made smaller without reducing the length or effectiveness of the rolling operation.

In prior devices of this kind, the bunch, after ejection from the manipulator, has 30 been cradled loosely for a moment until seized by the transfer device commonly used to carry the bunches to the shaper. This permitted loosening of the binder which had been tightened about the bunch during manipulation. It is, accordingly, another object of the invention to produce a bunch 35 manipulator in which the binder will be held against loosening from the time of ejection until the bunch is seized by the transfer device.

It has been found desirable to moisten the bunch prior to shaping. However, if moisture is applied to the bunch before or during the manipulating operation, the concave 45 member will collect the excess water which, together with the tobacco dust always present, will form a puddle through which the bunch will have to pass. By applying the moisture after the bunch has left the manipulator, the latter is kept dry. It is, there-

fore, still another object of the invention to provide an effective moistening device which will moisten either end of the bunch during its transfer from the bunch manipulator to the shaper. 55

Still another object is to provide suitable mechanism for centering the bunch after ejection from the manipulator, so that the bunch will be moistened at the right places and will arrive at the shaper in a properly 60 centered position for shaping thereby.

Another object is to provide a simple resilient mount for the concave member having no wearing parts, which will permit yielding of the concave member in a radial direction, while preventing undesirable lateral tilting with respect to the drum. 65

With these and other objects not specifically mentioned in view, the invention consists of certain constructions and combinations which will be hereinafter fully described and then set forth in the hereunto appended claims. 70

In the accompanying drawings which form a part of this specification and in which like characters of reference designate the same or like parts: 75

Fig. 1 is a side elevation of the improved cigar bunch manipulator;

Fig. 2 is a top view of the device shown 80 in Fig. 1;

Fig. 3 is a front elevation of the same;

Fig. 4 is a rear elevation of the same, partly in section; and

Fig. 5 is a detail view in side elevation 85 showing the bunch ejecting mechanism.

In carrying the invention into effect, there is provided a rotating drum, a member having a surface encircling the major portion of the circumference of the drum and spaced from the drum less than the diameter of a bunch to slightly squeeze cigar bunches between said surface and the drum, and this member has an opening at one side of the drum to receive the bunches between 90 said surface and the drum in order to roll them in a path approximately circumscribing the drum and to permit subsequent ejection of the bunches at a position adjacent the receiving position. The best construc- 95 100

tions of the invention will also include transfer means to seize and forward the ejected bunches to the shaper, together with means for holding the binders of the bunches against loosening from the moment of ejection until the bunches are seized by said transfer means. In the preferred construction, there will be provided in combination with the cigar bunch manipulator, a transfer means for forwarding the bunches to the shaper, together with means in the path of said transfer means for moistening either end of the cigar bunches to prepare the same for the shaping operation. The above means may be widely varied in construction within the scope of the claims, since the particular machine selected to illustrate the invention is but one of many possible embodiments of the same. The invention therefore is not to be restricted to the specific construction shown and described.

Referring to the drawings, as shown in Figs. 1 to 4, the freshly rolled bunch B is delivered from the rolling table 6 to the manipulator by a transfer 7. At the manipulator the bunch is delivered through an opening in the concave member 8 into the space between said concave member and the side of a rotating drum 9, mounted on the shaft 10, supported by a bracket 11 and driven by a sprocket 12 and a chain 13 from the cigar machine. The concave member 8 has a cylindrical surface 8^a encircling the major portion of the drum, and this surface is spaced from the drum a distance slightly less than the diameter of a bunch to lightly squeeze said bunch between the drum and the surface. To be readily removable for cleaning, the drum 9 is held in place by lever 14, which is locked by the plunger 15 held in tension by the compression spring 16, the end of the shaft 12 being bored to receive the plunger and the spring.

To permit radial movement of the surface 8^a with respect to the drum, the concave member 8 is mounted by two pairs of resilient rods 17 and 18 parallel to each other and the axis of the drum, which are fastened at two positions along their length to the concave member by the blocks 19 and at another position along their length to the pedestal or support 20 by the blocks 21, each of said blocks serving to lock the two parallel rods together. This method of mounting the concave member permits movement of the member only in a direction perpendicular to the axis of the drum, so that the concave member must always move with its rolling surface parallel to the axis 60 of the drum. Thus, the high or hard spots in the bunch must take most of the pressure, which pressure, by the arrangement of the resilient rods 17 and 18 shown, is made substantially uniform around the circumference of the drum.

After a bunch has been delivered between the concave member and the rotating drum, it is rolled almost completely around the drum and ejected from under the concave member by the rolling action of the drum at a position adjacent the delivery position. This rolling action tightens the binder around the bunch and it has been found that if the binder can be held in this tightened position until it reaches the shaper, a more perfect cigar will result. For this purpose, a support or cradle 23 is provided which, together with fingers 24 and bracket 25, form a gripper. Bracket 25 is pivoted on a pin 26 of the gripper support 27. The fingers 24 are pressed towards the cradle or support 23 by a compression spring 28, to thereby lightly grip the ejected bunch.

While the bunch is in the manipulator, the cradle 23 is in its low position shown in dotted lines in Fig. 5, but ejection of a bunch actuates said gripper through the fingers 29 projecting from the end of the concave member 8 to raise the gripper into engagement with the bunch. The finger 29 is pivotally mounted by means of a shaft 31 on the concave member 8 and a lever 30 also secured to the shaft 31 operates the gripper as a result of lifting of the finger 29 by the ejected bunch. Finger 29 is spring pressed against the drum by a torsion spring 32. Accordingly, when a bunch is ejected, the finger 29 is lifted and through the lever 30 connected by a pin 34, the cradle is lifted under the bunch and the bunch is rolled by the drum between said cradle and the finger 24, and is thereby held without the binder being released. The limiting positions of the cradle are controlled by the adjusting screws 35 on bracket 27.

To prevent the bunch from arriving in the shaper when not properly centered, the bunch centering means or positioners 36 on either side of the gripper are employed (Figs. 2 and 3), the shafts 37 of which reciprocate in supporting brackets 38. These shafts are actuated by operating levers 39 and 40, which have blocks 41 sliding in fixed collars 42 fastened to said shafts. The levers 39 and 40 are fulcrumed on the brackets 38 and are actuated from the cigar machine in timed relation to the operation of the manipulator by rod 43 attached to the end of one arm of the double armed lever 39. The second arm of the lever 39 is connected with lever 40 by rod 44. Positioners 36 are on the center line of the bunch as its rests in the gripper, and when reciprocated to their inner position, the bunch will be properly centered for transfer to the shaper.

After being centered, the bunch is forwarded by the transfer 22 for shaping. During forwarding, both ends of the bunch engage with the moistened wicks 45 (Figs. 120

1 and 4) suspended in the path of the bunch from the bent bars 46 attached to a bracket 47 which is fastened to the pedestal 20. The amount of moisture applied to the bunch is regulated by the width of the 5 wicks, and by their position on the horizontal ends of the bars 46. To periodically moisten the ends of the wicks, cups 48 attached to a bracket 49 and guided by rods in lugs 51 of pedestal 28, are reciprocated 10 vertically so that the wicks are dipped in the cups when the cups are in their uppermost position. Vertical reciprocation of these cups is caused by a rod 52 attached to the bracket 49, which engages a bar 53 projecting from a reciprocating element of the shaper.

What is claimed is:

1. In a cigar bunch manipulator, the 20 combination with a rotating drum, of a member having a surface encircling the major portion of the circumference of the drum and spaced therefrom less than the diameter of a bunch to squeeze cigar 25 bunches between said surface and the drum, said member having an opening at one side of the drum to receive the bunches between 30 said surface and the drum for rolling movement in a path approximately circumscribing said drum and to permit subsequent 35 ejection adjacent the receiving position, transfer means to seize and forward the ejected bunches, and means for holding the binders thereof against loosening from the moment of ejection until the bunches are seized by said transfer means.

2. In a cigar bunch manipulator, the 40 combination with a rotating drum, of a member having a surface encircling the major portion of the circumference of the drum and spaced therefrom less than the diameter of a bunch to squeeze cigar bunches 45 between said surface and the drum, said member having an opening at one side of the drum to receive the bunches between said surface and the drum for rolling movement in a path approximately circumscribing said drum and to permit subsequent 50 ejection adjacent the receiving position, transfer means to seize and forward the ejected bunches, and means for holding the binders thereof against loosening from the moment of ejection until seized by said transfer means, including a bunch actuated 55 gripper.

3. In a cigar bunch manipulator, the 60 combination with a rotating drum, of a member having a surface encircling the major portion of the circumference of the drum and spaced therefrom less than the diameter 65 of a bunch to squeeze cigar bunches between said surface and the drum, said member having an opening at one side of the drum to receive the bunches between said surface and the drum for rolling movement in a

path approximately circumscribing said drum and to permit subsequent ejection adjacent the receiving position, transfer means to seize and forward the ejected bunches, and means for holding the binders of said 70 bunches against loosening from the moment of ejection until seized by said transfer means, including spring pressed fingers co-operating with the drum to receive the bunches as they are ejected, and means operated by said fingers to successively grip the bunches and swing the same into the range of action of the transfer means.

4. In a cigar bunch manipulator, the combination with a rotating drum, of a member 80 having a surface encircling the major portion of the circumference of the drum and spaced therefrom less than the diameter of a bunch to squeeze cigar bunches between said surface and the drum, said member 85 having an opening at one side of the drum to receive the bunches between said surface and the drum for rolling movement in a path approximately circumscribing said drum and to permit subsequent ejection adjacent the receiving position, and spaced 90 resilient rod mounts for said member yieldable only in a plane perpendicular to the axis of the drum to permit a radial movement but prevent lateral tilting of said surface with respect to said drum.

5. In a cigar machine, the combination 100 with means for manipulating cigar bunches and then ejecting the same, of transfer means for seizing and forwarding the ejected bunches, and means for holding the binders thereof against loosening from the moment of ejection until the bunch is seized by said transfer means.

6. In a cigar machine, the combination 105 with means for manipulating cigar bunches and then ejecting the same, of transfer means for seizing and forwarding the ejected bunches, and means for holding the binders thereof against loosening from the moment of ejection until the bunch is seized by said transfer means, said means for holding the binders including a bunch actuated gripper.

7. In a cigar machine, the combination 115 with means for manipulating cigar bunches and then ejecting the same, of transfer means for seizing and forwarding the ejected bunches, and means for holding the binders thereof against loosening from the moment of ejection until the bunch is seized by said transfer means, said means for holding the binders including spring pressed fingers bearing on said bunches as they are ejected, and means operated by said fingers to successively grip said bunches and swing the same into the range of action of the transfer means.

8. In a cigar machine provided with a 120 bunch shaper, the combination with a cigar 125

bunch manipulator, of transfer means for forwarding bunches from said manipulator to the shaper and wicks in the path of said transfer means for moistening either end of the cigar bunches.

5. 9. In a cigar machine provided with a bunch shaper, the combination with a cigar bunch manipulator, of transfer means for forwarding bunches from said manipulator to the shaper and means in the path of said transfer means for moistening either end of the cigar bunches, said means including wicks suspended with their pendant ends in the path of the bunch.

10. 15. In a cigar machine provided with a bunch shaper, the combination with a cigar bunch manipulator, of transfer means for forwarding bunches from said manipulator to the shaper and means in the path of said transfer means for moistening either end of the cigar bunches, said means including wicks suspended in the path of the bunch, and vertically reciprocating cups for periodically moistening said wicks.

20. 25. The combination with means for forwarding cigar bunches, of means for moistening said bunches during the forwarding movement including a wick suspended with a pendant end in the path of the bunch, and 30 a vertically reciprocating cup for periodically moistening said end.

35. 40. 12. In a cigar bunch manipulator, the combination with a pair of relatively moving members coacting to roll a bunch between them, of a resilient mount for securing one of said members to a support comprising a pair of parallel resilient rods, both secured at one position along their length to one of the members and at another position along their length to the support.

In testimony whereof, I have signed my name to this specification.

JOHN FREDRIK HALSTEAD.
